UNITED STATES PATENT OFFICE.

ROBERT W. DONLEY, OF PHILADELPHIA, PENNSYLVANIA.

MOP AND WRINGER THEREFOR.

1,329,961.

Specification of Letters Patent.

Patented Feb. 3, 1920.

Application filed April 12, 1919. Serial No. 289,534.

To all whom it may concern:

Be it known that I, ROBERT W. DONLEY, a citizen of the United States, residing at Philadelphia, in the county of Philadelphia 5 and State of Pennsylvania, have invented new and useful Improvements in Mops and Wringers Therefor, of which the following is a specification.

The invention relates to brushing and 10 scrubbing and more particularly to mops and mop apparatus, and has for an object to provide a mop for use in swabbing a floor or surface, and a wringer for wringing out the mop.

15 The invention comprehends among other features, a simple construction or device, including the usual handle carrying a frame on which is arranged a mop holder, carrying a mop or swab, the holder being adapted to 20 slide upon the frame so that the swab can be moved into an extended position or held relatively loose upon the holder, with a wringer provided for the purpose of imparting a twisting action to the mop or swab 25 when it is in one position, the swab when in the other or loose position on the holder, being adapted to be moved back and forth over the surface to be cleaned for the purpose of removing any dirt or other foreign 30 matter from the said surface.

I am aware that various forms of mops and wringers have been used heretofore and in which the wringer is a part of the mop structure, but in many of these instances, the 35 constructions are impractical and expensive in their manufacture; further the construction is such that the mops are quickly worn out and can not be readily repaired.

40 In my device I aim to employ a mop which is of a simple construction and in which the parts are so arranged relative to each other that the mop will withstand great wear and tear, permit of the application of a new swab when the old one becomes unfit for further 45 use, and in which various of the other parts are arranged so that they can be readily replaced.

50 In the further disclosure of the invention, reference is to be had to the accompanying drawings, constituting a part of this specification, in which similar characters of reference denote corresponding parts in all the views, and in which

Figure 1— is a perspective view of the 55 mop showing the swab in position for use.

Fig. 2— is a side view showing the swab extended and subjected to the action of the wringer.

Fig. 3— is a section on the line 3—3 in 60 Fig. 1; and

Fig. 4— is a fragmentary enlarged view showing the manner of securing one end of the swab.

Referring more particularly to the views, the numeral 10, indicates a handle or holder, 65 carrying at its front end a frame 11, in the nature of a tubular stem 12, into which one end of the handle 10 is inserted, the forward end of the stem being formed into a fork 13, provided with openings 14. Passing 70 through the openings 14 and mounted to slide upon the forked end or stem of the frame, is a wire-like swab holder 15, the inner end of which is bent to form an open loop 16, partially encircling the stem of the frame and adapted to slide thereon, the forward end of the swab holder having a straight portion 17 over which the swab passes with a locking bar 18, suitably mounted 75 upon the swab holder and adapted for locking engagement therewith to hold the front end of the swab upon the holder.

The stem of the frame is in the nature of a bearing, having a crank handle 19, mounted to turn thereon as shown and which is a 85 part of my form of wringer, said crank handle at its upper and inner end carrying a suitable handle 20 and adapted to have a straight portion 21, lie substantially parallel 90 with the inner end of the stem of the frame and in fact engage with a locking lug 22 thereon, to hold the crank handle against relative movement, the lower or forward end of said crank handle being formed with an open loop 23 through which the other end 95 of the swab passes, said loop being left open so that the swab can be readily removed. It will be seen that when the inner end of the swab has been removed from the loop and it is desired to entirely remove the swab 100 from the swab holder, the securing bar is first unlocked and then it will be seen that an encircling sleeve 24 normally covering the free ends of the swab holder at the front end, can be slid to one side, thus providing 105 sufficient space for the front end of the swab

to be removed from the swab holder, it being understood that the swab is only removed when it is desired to replace the same with a new swab or for some other similar reason.

Aside from having the upper and rear portions of the crank handle adapted for engagement with the locking lug on the inner end of the frame, it will be seen that when the swab holder is slid rearwardly upon the frame, the partially closed loop will pass over the upper portion of the crank handle and bearing against the latter, will lock the crank handle against further movement, said position of the inner end of the swab holder and the engagement of the loop thereof, with the crank handle, also locking the swab holder against an accidental longitudinal movement upon the frame. In this manner one part, namely the crank handle, will act as a lock for the other part, namely the swab holder and vice versa and thus the mop can be readily used upon the floor or surface so that the swab will effectively perform its work without danger of any loose or wobbling parts. When it is desired to wring out the swab, the swab holder is slid forwardly upon the frame, thus unlocking the former and also the crank handle and this forward movement of the holder naturally causes the swab to be straightened out or extended so that subsequent turning of the crank handle will tend to twist the swab so as to wring out any water in the swab and thus partially dry the latter.

The swab holder is preferably provided with a suitable knob or handle 25, facilitating the operation of moving the swab holder backwardly and forwardly in order to move the swab into an extended or retracted position.

From the foregoing description it will be seen that the device described is of a simple construction, consisting of few parts that are easily assembled and can not readily get out of order. With this combination it will be apparent that the effective operation of

the mop or swab for the purpose desired, can be readily performed.

Having described my invention, I claim,—

1. A mop and wringer therefor, comprising a frame, a swab holder mounted to slide upon the frame and movable into an extended or retracted position thereon, a mop on the forward end of the holder and having its forward part movable with the holder into an extended or retracted position, a crank handle mounted to turn upon the frame and having an end of the swab connected thereto and means on the swab holder and adapted for engagement with the crank handle when the mop holder is retracted on the frame, for relatively locking said crank handle and swab holder.

2. A mop and wringer therefor, the combination with a frame and an accompanying handle, of a swab holder slidably carried by the frame and movable into a retracted position thereon, a swab for the swab holder, a notatable wringer element carried by the frame and having one end connected with the swab and means forming a part of the holder and engaging the frame for simultaneously locking said holder in retracted position on the frame and said wringer against rotation.

3. A mop and wringer therefor, comprising a frame, a swab holder mounted to slide upon the frame, a disjunctable cross bar, forming a part of said holder and supporting the swab thereon, means on the holder and cooperating with the cross bar to secure the swab against the holder at the front, a wringer element mounted on the frame and having the end of the swab detachably connected thereto and means forming a part of said swab holder and upon retracted movement of the swab holder, adapted to engage with the wringer element and lock said swab holder and wringer element relative to the frame.

In testimony whereof I affix my signature.

ROBERT W. DONLEY.
